DESIGN FOR A GLASS NAPPY OR ARTICLE OF SIMILAR NATURE

Belle Kogan, New York, N. Y., and Albert H. Nicholson, Columbus, Ohio, assignors to The Federal Glass Company, Columbus, Ohio, a corporation of Ohio

Application December 16, 1940, Serial No. 97,348

Term of patent 3½ years

To all whom it may concern:

Be it known that we, Belle Kogan and Albert H. Nicholson, citizens of the United States of America, residing, respectively, at New York, in the county of New York and State of New York, and at Columbus, in the county of Franklin and State of Ohio, have invented a new, original, and ornamental Design for a Glass Nappy or Article of Similar Nature, of which the following is the specification, reference being had to the accompanying drawing, forming a part hereof.

We claim:

The ornamental design for a glass nappy or article of similar nature, substantially as shown.

BELLE KOGAN.
ALBERT H. NICHOLSON.
